United States Patent [19]
Humphreys

[11] **Patent Number:** **Des. 277,177**
[45] **Date of Patent:** ** Jan. 15, 1985

[54] **CONTINUOUS ELECTRICAL TRACK SYSTEM**

[75] Inventor: **Michael Humphreys, London, England**

[73] Assignee: **Electrak International, Ltd., London, England**

[**] Term: **14 Years**

[21] Appl. No.: **345,319**

[22] Filed: **Feb. 3, 1982**

[30] **Foreign Application Priority Data**

Aug. 6, 1981 [GB] United Kingdom 1001839

[52] U.S. Cl. **D13/13; D13/24**

[58] Field of Search D13/12, 13, 24, 30;
339/20-23
